UNITED STATES PATENT OFFICE

GEORGE ERNEST CREED, OF LONDON, ENGLAND, ASSIGNOR TO D. GESTETNER,
LIMITED, OF LONDON, ENGLAND.

DUPLICATING MACHINE

Application filed March 31, 1930, Serial No. 440,518, and in Great Britain June 18, 1929.

This invention relates to stencil duplicating machines of the type with which a viscous or pasty ink is employed, the ink being distributed over the surfaces of impermeable inking cylinders with the aid of so-called waver rollers, that is to say rollers to which movement is imparted for the purpose of assisting in the distribution of the ink over the surface of the inking cylinders whereby the ink is forced through the openings in the stencil.

With duplicating machines of this kind one or a pair of such waver rollers are provided to which axial motion is imparted by a lever oscillating about an axis at right angles to the axis of rotation of the inking cylinder or inking cylinders, the ends of the waver rollers being engaged in open bearings provided on these levers, of which in 20 a known arrangement there are two, located at opposite ends of the inking cylinders and in order to remove the waver roller, or the waver rollers as the case may be, it is necessary to engage the ends of the spindles thereof and to raise the same out of the said bearings after which the waver rollers or roller may be moved axially and withdrawn through an opening in the side frame of the machine, the replacement of the waver 30 rollers involving the insertion of the same through the opening and the engagement of the ends of the spindles thereof in the aforesaid bearings.

One of the objects of the present invention is to provide means adapted to facilitate the removal for cleaning or other purposes and the replacement of the waver rollers.

One feature of the invention comprises 40 the provision of a plurality of waver rollers in association with an inking cylinder and the provision of means whereby to one or certain thereof axial motion is imparted in the normal operation of the machine.

45 A further feature of the invention consists, broadly, in the provision of means associated with the frame of the machine adapted to be actuated to bring the waver roller or waver rollers after they have been inserted through an opening in the side

frame of the machine so as to rest upon an inking cylinder, into the appropriate working position.

Thus, in accordance with the invention, means may be provided adapted to be actuated, when the waver roller or waver rollers as the case may be have been passed through the opening in the side frame of the machine and rest upon one of the inking cylinders thereof, to engage against the spindles of the waver roller or the spindles of the waver rollers, as the case may be, and bring the same into the operative position with respect to the inking cylinder and optionally to cause the waver roller or one or both of the waver rollers, when a plurality thereof are provided, to engage the means adapted to impart axial motion thereto during the normal operation of the machine.

In one construction in accordance with the invention, in which a pair of inking cylinders are provided over which the stencil, connected to flexible bands in driving engagement with the cylinders, is caused to travel there is provided on each of the side frames a pair of levers adapted to be moved about a common axis to cause the levers to engage or bear against the spindles of the waver rollers and thereby to move them towards the plane in which the axes of rotation of the inking cylinders lie.

Conveniently each pair of levers is mounted upon the spindle of one, and preferably the upper, of the inking cylinders.

Normally the pair of levers will be interconnected by means adapted to cause each member of a pair to move simultaneously and in corresponding degree or extent about its axis.

Thus, for instance, each lever of a pair 90 may be provided with means engaging a further lever or the like by the motion of which each member of the related pair of levers will be caused to move correspondingly in degree or extent about their common 95 axis.

To this end each member of a pair of levers may be provided with a slot of suitable form in which is engaged a pin provided on the further lever which is conveniently 100

formed with a thumb piece to facilitate its actuation.

To constrain the two members of a pair of levers to move towards one another in bringing the waver rollers into their operative position a spring connection may be provided between the levers.

Ordinarily the portions of the levers adapted to bear against or to engage the spindles of the waver rollers are conveniently provided with curved surfaces adapted to facilitate the movement of the waver rollers into their working position.

For engaging one or both of the waver rollers with means whereby during the operation of the machine it may be moved in an axial direction, the lever adapted to oscillate about an axis at right angles to the axis of rotation of the inking cylinders for securing such motion of the waver rollers may be provided with a boss adapted to engage a circumferential groove in the spindle of the waver roller.

For facilitating such engagement the end of the waver roller spindle to which axial motion is imparted is preferably provided with two reversely tapered or coned portions with a groove between the adjacent larger extremities of these portions while the base of the boss on the lever is coned to co-operate with said portions when the lever is oscillated into ensuing engagement of the boss with the groove.

Further, the spindles of the waver rollers may be provided with portions of reduced diameter at each end, adapted to bear against the arms of the levers in order to limit the axial motion imparted to the waver rollers and to facilitate the axial positioning of the same with respect to the inking cylinder with which the waver roller or rollers will contact.

Where a pair of waver rollers is provided and only to one of them axial motion is intentionally imparted, the waver roller which is designed to be merely subjected to rotational motion may be provided at each end with portions tapered in reverse directions to a common zone of reduced diameter in which one of the levers, adjacent to each end of the inking cylinder, will engage and thus tend to hinder or prevent the roller being moved axially during the normal operation of the machine.

The invention will be described further in detail with reference to the accompanying drawings, in which

Figure 1 is a fragmentary end elevation of a duplicating machine in accordance with the invention,

Figure 2 being a corresponding plan view with certain portions broken away or removed in order that the essential details of the invention may be more clearly seen.

In the drawings, 1 and 1a represent the

side members of the frame of the machine.

The inking cylinders are indicated by the references 2 and 2a, the upper of these cylinders being shown removed in Figure 2. 3 in Figure 1 is an endless flexible stencil carrier which is arranged in known manner to travel over the inking cylinders. On the spindle 4 of the upper inking cylinder are pivoted two levers 5 and 5a connected together by a spring 6 and provided with slots 7 and 7a in which engages a pin 8 provided on the lever 9 pivoted at 10 to the frame of the machine.

By motion of the lever 9 in a downward direction the levers 5 and 5a may be moved about their pivotal connection with the spindle of the upper inking cylinder to facilitate inserting the waver rollers 11 and 11a through an opening 12 in the side members of the frame of the machine. These rollers are respectively provided with knobs 13 and 13a to facilitate handling them and on the spindle 14 of one of the rollers are provided two reversely directed tapered portions 15, between which is a zone of reduced diameter 16 in which the arms of the levers 5 will engage to secure the roller 11 from axial motion.

The spindle 17 of the waver roller 11a is provided at both ends with portions of reduced diameter 18 which are engaged by the levers 5a in such manner as to permit axial motion of the roller from the position shown in full line in Figure 2 to the position shown in dotted line in the said figure. One end of the spindle is also provided with two conical portions 19 and 20, between the bases of which conical portions a groove 21 is left and in this groove engages a boss 22 secured on one end of the bell crank lever 23 pivotally mounted by the screw 24 to the side frame of the machine and provided with a hole 25 engaging a lever 26 pivotally mounted so that it may be oscillated about the axis of the spindle 27 of the inking cylinder 2a by means not shown in the drawings but of any suitable character actuated through a handle or other source of motion whereby the inking cylinders and other moving parts of the machine are operated. The oscillatory motion thus imparted to the lever causes it to move the lever 23 about its pivotal connection with the side of the frame and in consequence of the engagement of the boss 22 in the groove 21, axial motion is imparted to the waver roller 11a.

The base of the boss 22 is formed as a truncated cone 28, the peripheral surfaces of which are arranged to cooperate with the conical portions 19, 20 provided on the end 125 of the spindle 17 of the waver roller 11a to facilitate engagement of the boss in the groove 21.

In placing the waver rollers in position it is merely necessary in the construction 120

above illustrated to depress the levers 9 thereby moving apart the ends of the levers 5 and 5a to permit the insertion of the waver rollers 11 and 11a, the knobs 13 and 13a assisting in the manipulation of the rollers in this operation. The two waver rollers having been so inserted and located in the approximate positions which they should occupy the levers 9 are raised whereby the 10 arms of the levers 5 and 5a, arranged on each of the side members of the frame of the machine, are brought together and are thus caused to move the waver rollers towards the plane in which the axes of the 15 inking cylinders lie.

Actuation of the machine through the driving means provided for this purpose will effect rotation of the inking cylinders and also oscillation of the lever 26 and 20 through it the oscillation of the lever 23 thus, if the boss 22 is not already engaged in the groove 21, causing the conical surface of the base 28 of the boss 22 to contact with one or other of the conical portions 19 and 25 20 on the spindle of the waver roller, one end of the latter will thereby be raised due to the conical portions of the spindle riding over the base 28 until the boss 22 is brought into register and engages with the groove 30 21 when, the end of the spindle descending into its normal position, continued oscillatory motion of the lever 23 will impart to the waver roller its normal axial motion.

While in the detailed description given 35 above reference has been made to a construction comprising pivoted levers, whereby the waver roller or waver rollers are brought into their appropriate position, it is to be understood that the invention is not limited to 40 constructions comprising levers, as any mechanical equivalent of such members may be employed for the purpose. For instance, members may be slidably mounted in guides on the machine in such manner that they 45 may be moved into or out of position to engage against the ends of the spindles of the waver rollers.

Having now described my invention, what 50 I claim as new and desire to secure by Letters Patent is:—

1. A stencil duplicating machine comprising a frame, a plurality of impermeable inking cylinders rotatably mounted in said frame adapted to force the ink through 55 openings in the stencil, waver rollers associated with said inking cylinders for assisting in distributing the ink thereover, openings in the frame through which the waver rollers may be inserted and means associated with the frame adapted on the insertion of the waver rollers to bring the 60 same into the operative position with respect to the inking cylinders.

2. A stencil duplicating machine comprising a frame, a plurality of impermeable in-

ing cylinders rotatably mounted in said frame adapted to force the ink through openings in the stencil, means for rotating the inking cylinders, waver rollers associated with said inking cylinders for assisting in distributing the ink thereover, means for imparting axial motion to a waver roller in the normal operation of the machine, 70 openings in the frame through which the waver rollers may be inserted, means associated with the frame adapted on the insertion of the waver rollers to bring the same into the operative position with respect to the inking cylinders and to cause a waver roller to engage the means adapted 75 to impart axial motion to it.

3. A stencil duplicating machine comprising a frame, a plurality of impermeable inking cylinders rotatably mounted in said frame adapted to force the ink through 80 openings in the stencil, waver rollers associated with said inking cylinders for assisting in distributing the ink thereover, openings in the frame through which the waver rollers may be inserted, a pair of levers adjacent to one end of an inking cylinder, a common pivotal mounting for said levers, a pair of levers adjacent to the other end of the said cylinder, a common pivot co-axially with the pivotal mounting of the first-mentioned levers, means associated with said pair of levers adapted to cause each member of a pair to move correspondingly about the axis of its pivotal mounting into a position adapted to permit the waver rollers to be inserted through openings in the frame and thereafter to be moved into a position whereby the levers engage the waver rollers and constrain them into operative position with respect to the inking cylinders. 90

4. A stencil duplicating machine comprising a frame, a plurality of impermeable inking cylinders rotatably mounted in said frame adapted to force the ink through 95 openings in the stencil, means for rotating the inking cylinders, waver rollers associated with said inking cylinders for assisting in distributing the ink thereover, means for imparting axial motion to a waver roller in the normal operation of the machine, openings in the frame through which the waver rollers may be inserted, 100 a pair of levers adjacent to one end of an inking cylinder, a pivot common to said levers, a pair of levers adjacent to the other end of the said cylinder, a pivot common to the said levers co-axially with the pivot of the first-mentioned levers, means associated with each of said pairs of levers adapted to cause each member of a pair to move correspondingly about the axis of its pivot into a position adapted to permit the waver rollers to be inserted through the openings 105 in the frame and thereafter to be moved into a position whereby the levers engage 110

115

120

125

the waver rollers and constrain them into an operative position with respect to the inking cylinders.

5. A stencil duplicating machine comprising a frame, a pair of impermeable inking cylinders rotatably mounted one above the other in said frame, a pair of levers pivotally mounted about the axis of the upper of said inking cylinders adjacent to one end thereof, a further pair of levers pivotally mounted about the axis of said inking cylinder adjacent to the other end thereof, the arms of said levers extending in a downward direction towards the lower inking cylinder, means adapted to move the levers about the axis of the upper inking cylinder thereby increasing the distance between the ends of the said levers and means adapted to constrain the ends of the said levers to move in the reverse direction.

6. A stencil duplicating machine comprising a frame, a pair of impermeable inking cylinders rotatably mounted one above the other in said frame, waver rollers associated with the inking cylinders for assisting in distributing the ink thereover, openings in the frame through which the waver rollers may be passed, a pair of levers pivotally mounted about the axis of the upper of said inking cylinders adjacent to one end thereof, a further pair of levers pivotally mounted about the axis of said inking cylinders adjacent to the other end thereof, the arms of said levers extending in a downward direction towards the lower inking cylinder, means adapted to move the levers about the axis of the upper inking cylinder thereby increasing the distance between the ends of the said levers and means adapted to constrain the ends of the said levers to move in the reverse direction to bring the waver rollers when inserted through the opening in the frame and bearing upon the lower inking cylinder into their operative position.

7. A stencil duplicating machine comprising a frame, a pair of impermeable inking cylinders rotatably mounted one above the other in said frame, waver rollers associated with the inking cylinders for assisting in distributing the ink thereover, each of said waver rollers comprising a roller body and a spindle extending beyond the ends of the roller body, openings in the frame through which the waver rollers may be passed, a pair of levers pivotally mounted about the axis of the upper of said inking cylinders adjacent to one end thereof, a further pair of levers pivotally mounted about the axis of said inking cylinders adjacent to the other end thereof, the arms of said levers extending in a downward direction to the lower inking cylinder, means adapted to move the levers about the axis of the upper inking cylinder thereby increasing the distance between the ends of the said levers

and means adapted to constrain the ends of the said levers to move in the reverse direction to cause the ends of said levers to engage against the spindles of the waver rollers and thereby bring the waver rollers into their operative position.

8. A stencil duplicating machine comprising a frame, a pair of impermeable inking cylinders rotatably mounted one above the other in said frame, a pair of levers pivotally mounted about the axis of the upper of said inking cylinders, adjacent to one end thereof, a further pair of levers pivotally mounted about the axis of said inking cylinders adjacent to the other end thereof, the arms of said levers extending in a downward direction towards the lower inking cylinder, slots in each pair of levers, a further lever associated with each pair of levers pivotally connected with the frame of the machine and a pin on each of the further levers engaging in the slots in the adjacent pair of levers adapted, by moving the further lever about its pivot, to cause the first mentioned levers to move about their pivots and a spring connected with each pair of levers adapted by appropriate operation of the further levers to constrain the ends of the associated levers to move towards one another.

9. A stencil duplicating machine comprising a frame, a pair of impermeable inking cylinders rotatably mounted one above the other in said frame, waver rollers associated with the inking cylinders for assisting in distributing the ink thereover, openings in the frame through which the waver rollers may be passed, a pair of levers pivotally mounted about the axis of the upper of said inking cylinders adjacent to one end thereof, a further pair of levers pivotally mounted about the axis of said inking cylinder adjacent to the other end thereof, the arms of said levers extending in a downward direction towards the lower inking cylinder, slots in each pair of levers, a further lever associated with each pair of levers pivotally connected with the frame of the machine and a pin on each of the further levers engaging in the slots in each member of an adjacent pair of levers adapted by moving the further lever about its pivot to cause the adjacent pair of levers to move about their pivots and a spring connected with each pair of levers adapted by appropriate operation of the said further lever to constrain the ends of the associated pair of levers to move towards one another.

10. A stencil duplicating machine comprising a frame, a plurality of impermeable inking cylinders rotatably mounted one above the other in said frame, a pair of waver rollers associated with said inking cylinders for assisting in distributing the ink thereover, a spindle extending beyond

the end of one of the waver rollers, two reversely tapered portions, a groove between the larger ends of the tapered portions on the portion of the spindle so extending, a lever pivoted on the frame of the machine adapted to oscillate about an axis at right-angles to the axis of rotation of the inking cylinders thereof and a boss on one end of said lever adapted to engage in the groove 10 in the waver roller spindle.

11. A stencil duplicating machine comprising a frame, a plurality of impermeable inking cylinders rotatably mounted one above the other in said frame, a pair of 15 waver rollers associated with said inking cylinders for assisting in distributing the ink thereover, a spindle extending beyond the end of one of the waver rollers, two reversely tapered portions with a groove 20 between them on the portion of the spindle so extending, a lever pivoted on the frame of the machine adapted to oscillate about an axis at right-angles to the axis of rotation of the inking cylinders thereof, a boss 25 on one end of said lever adapted to engage in the groove in the waver roller spindle and a conical base on said boss adapted to facilitate such engagement.

12. A stencil duplicating machine comprising a frame, a plurality of impermeable inking cylinders rotatably mounted one above the other in said frame, a pair of waver rollers associated with said inking cylinders for assisting in distributing the ink 35 thereover, a spindle extending beyond the end of one of the waver rollers, two reversely tapered portions with a groove between them on the portion of the spindle so extending, a lever pivoted on the frame 40 of the machine adapted to oscillate about an axis at right-angles to the axis of rotation of the inking cylinders thereof and a boss on one end of said lever adapted to engage in the groove in the waver roller spindle, 45 a groove in each end of the spindle of the other waver roller adapted to be engaged by one member of each pair of pivoted levers to restrain the said waver roller from axial motion in the normal operation of the 50 machine.

13. A stencil duplicating machine comprising a frame, a plurality of impermeable inking cylinders, rotatably mounted one above the other in said frame, a pair of 55 waver rollers associated with said inking cylinders for assisting in distributing the ink thereover, a spindle extending beyond the end of one of the waver rollers, two reversely tapered portions with a groove 60 between them on the portion of the spindle so extending, a lever pivoted on the frame of the machine adapted to oscillate about an axis at right-angles to the axis of rotation of the inking cylinders thereof, a boss 65 on one end of said lever adapted to engage

in the groove in the waver roller spindle and a conical base on said boss adapted to facilitate such engagement, a groove in each end of the spindle of the other waver roller adapted to be engaged by one member of each pair of pivoted levers to restrain the 70 said waver roller from axial motion in the normal operation of the machine.

In testimony whereof I have signed my name to this specification.

GEORGE ERNEST CREED.
